(57) **CLAIM**

The ornamental design for a vehicle side light as shown and described.

DESCRIPTION

FIG. 1 is an orthographic front view showing our new design of a vehicle side light.

FIG. 2 is an exploded, orthographic view of the vehicle side light.

FIG. 3 is a front elevational view of the vehicle side light.

FIG. 4 is an elevational left side view of the vehicle side light.

FIG. 5 is an elevational right side view of the vehicle side light.

FIG. 6 is a top plan view of the vehicle side light; and, FIG. 7 is a bottom plan view of the vehicle side light.

The dashed lines shown in the figures are for illustrative and environmental purposes only, are disclaimed, and form no part of the claimed design.

1 Claim, 6 Drawing Sheets
